WEARING BLOCK FOR STEEL RETAINERS

Filed Dec. 16, 1927

FIG.-4.

FIG.-3.

FIG. 2.

INVENTOR.
Charles C. Hansen
BY Robert G. Oden
HIS ATTORNEY

UNITED STATES PATENT OFFICE

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY

WEARING BLOCK FOR STEEL RETAINERS

Application filed December 16, 1927. Serial No. 240,485.

This invention relates to rock drills, but more particularly to a wearing block adapted to be attached to the yoke portion of a steel retainer of the type used for preventing ejection of the drill steel from the front head of the drill.

The objects of the invention are to protect the steel retainer against the wearing action of the drill steel, to insure an equal distribution of the force of the blow of the working implement over the entire yoke portion of the retainer and to reduce breakage of retainers of this type to a minimum.

Other objects will be in part obvious and in part pointed out hereinafter.

In the drawings illustrating a practical application of the invention,

Figure 1 is a side elevation of a steel retainer having the invention applied thereto,

Figure 2 is an end view of the wearing block and the retainer,

Figure 3 is an elevation showing another view of the wearing block, and

Figure 4 is an elevation of the yoke portion of a retainer illustrating the manner in which the wearing block may be placed on the yoke.

Referring more particularly to the drawings, the invention is shown applied to a steel retainer A of the type shown and described in United States Patent No. 1,000,036 entitled Tool steel retainer for percussive tools; granted to William Prellwitz August 8, 1911. The steel retainer accordingly has a yoke B to encircle a drill steel forwardly of a collar or projection to act as an abutment therefor for preventing ejection of such working implement from the rock drill whereby it is actuated.

The yoke B is provided with side arms C to which it is connected by means of curved portions D. At the rearward end of the side arms C are formed spiral springs E for absorbing the blows against the yoke, and the inner coils F of the spiral springs E are shaped to receive trunnions or pivots carried by the rock drill.

In accordance with the present invention, means are provided for protecting the yoke portion B of the retainer A against wear

ordinarily caused by the drill steel as well as to reinforce the yoke against the effects of the blows of a drill steel thereagainst. To this end a wearing block G of U-shape is disposed on the yoke B. The wearing block has a peripheral groove H to conform to and receive the yoke B. On the sides of the groove H are flanges J and K to engage the upper and lower surfaces L and O respectively of the yoke B.

The flange J terminates at a point short of the end of the wearing block and has on its innermost surface curved surfaces P to conform to the curvature of the curved portion D. This construction also enables the wearing block G to be readily disposed on the yoke B, particularly on retainers such as that illustrated in which the side arms near the yoke converge toward each other near the curved portion.

Preferably a depression Q is formed in the uppermost surface of the wearing block G to form a seat for the collar usually provided on working implements. The depression Q is of cylindrical formation of slightly larger diameter than the collar which it is adapted to accommodate and the wall R of said depression will also serve to prevent oscillation of the retainer from the path of such collar since, when the collar of the working implement rests on its seat, the wall R will engage the collar.

Convenient means are provided for securing the wearing block to the retainer. In the present instance the flange K carries a clip S which may be crimped against the rearward surface of the yoke B to maintain the wearing block on the yoke and also to hold it against movement with respect to the yoke. A slot T in the wearing block may be of any suitable size to accommodate working implements of the type and size usually used in connection with rock drills employing retainers of this type.

In assembling the wearing block on the retainer the wearing block may first be disposed between the side arms C in approximately the position illustrated in Figure 4 when used on a retainer such as that illustrated. In this position the peripheral

groove H will engage the curved portion D of the side arms C and the wearing block may then be readily moved into its proper operative position. After the wearing block has been thus disposed on the yoke B, the clip S may be crimped around the yoke to secure the wearing block immovably on the yoke.

By means of the present invention, the yoke B of the retainer will be fully protected against the wearing action of the drill steels since all the wear will occur on the wearing block, the wearing block may be readily replaced after it becomes unfit for use without necessitating long delays in the drilling operation as frequently happens in the case of breakage of the retainer.

Due to the present invention, the life of retainers of the type to which the present invention pertains may be extended considerably since a suitable striking surface may be at all times maintained for the implement collar and the force of the blows of such implement will be more equally distributed over the entire area of the yoke.

I claim:

1. In combination with a steel retainer having a yoke, means adapted to be attached to the yoke for protecting said yoke against the percussion of a drill steel collar.

2. In combination with a steel retainer having a yoke, a wearing block for protecting the yoke against the percussive wearing action of the collar of a drill steel, said wearing block having a groove to receive the yoke, and a clip on the wearing block for securing said wearing block to the yoke.

3. In combination with a steel retainer having a yoke, a wearing block for protecting the yoke against the percussive wearing action of the collar of a drill steel, said wearing block having a peripheral groove to receive the yoke, and a clip on the wearing block adapted to be crimped against one side of the yoke for holding the wearing block on the yoke.

4. In combination with a steel retainer having a yoke, a wearing block for protecting the yoke against the percussive wearing action of the collar of a drill steel, said wearing block having a peripheral groove to receive the yoke, a depression in the end of the wearing block to form a seat for the collar of a drill steel, and a clip on the side of the wearing block adapted to be crimped against the yoke for holding the wearing block on the yoke.

5. In combination with a steel retainer having a yoke, a U-shaped wearing block for protecting the yoke against the percussive wearing action of the collar of a drill steel, said wearing block having a peripheral groove to receive the yoke, a depression in one end of the wearing block to form a seat for the collar of a drill steel, and a clip on

the wearing block adapted to be crimped against the yoke for holding the wearing block on the yoke, said clip being located on one side of the peripheral groove.

6. In combination with a steel retainer having a yoke, a U-shaped wearing block for protecting the yoke against the effect of the blows of a drill steel, flanges on the wearing block to engage the upper and lower surfaces of the yoke, a depression in one end of the wearing block to form a seat for the collar of a drill steel, and a clip on one flange crimped against the yoke for holding the wearing block on the yoke.

7. In combination with a steel retainer having a yoke, a wearing block for protecting the yoke against the effect of the blows of a drill steel, said block fitting between the yoke and drill steel.

8. In combination with a steel retainer having a yoke, a wearing block for protecting the yoke against the effect of the blows of a drill steel, said block fitting between the yoke and drill steel, and securing means in the block extending around the yoke to secure them one to the other.

In testimony whereof I have signed this specification.

CHARLES C. HANSEN.
